UNITED STATES PATENT OFFICE.

MORTON M. WEIL, OF SCRANTON, PENNSYLVANIA, ASSIGNOR TO SAMUEL H. FRANK,
OF SCRANTON, PENNSYLVANIA.

COLLAR.

Application filed April 18, 1922. Serial No. 554,608.

To all whom it may concern:

Be it known that I, MORTON M. WEIL, a citizen of the United States, residing at Scranton, in the county of Lackawanna and State of Pennsylvania, have invented an Improvement in Collars, of which the following is a specification.

This invention relates to an improvement in collars and more particularly to the type 10 of collar of the turnover form and soft or unstiffened variety. In this type of collars, as heretofore constructed, it has been customary to weave the material from which the collars are made in strips and to cut the 15 collar entire from the strips of material and then to connect the parts of the collar along the edges thereof by a suitable binding. In this type of collar also the material has been so woven as to provide a weakened curvilinear line along which the parts of the 20 collar are folded to give the same a predetermined set to conform to the neck of the wearer. Now the object of my invention is the provision of a collar which is not only 25 woven in one piece to shape but is woven in a folded and set position, and also with the band member and flap member so reinforced as to provide in the collar a means for 30 strengthening the same and retaining it in position on the neck of the wearer to cause the collar to have the appearance of the usual type of starched stiff collar.

In the drawing:

Fig. 1 is a perspective view of a collar 35 made in accordance with this invention.

Fig. 2 is an elevation of the same.

Fig. 3 is a cross section on line 3—3, Fig. 1.

Fig. 4 is an elevation of an end portion of a collar showing another form of the invention.

Fig. 5 is a cross section on line 5—5, Fig. 4, and

Fig. 6 is a section on line 6—6, Fig. 1.

Referring to the drawing, and particularly 45 to Figs. 1, 2, 3 and 6, the collar made in accordance with this invention comprises a band member 10 and a flap member 11. These parts of the collar are woven to shape in a folded and set position in the form indicated in Fig. 2, and the material is preferably woven solid and in strips so that the strips may be cut transversely along lines

of any desired configuration to form the collars from the strips of material.

The edge of the band member 10 is preferably reinforced as indicated at 13 by crowding the warps or otherwise in the weaving, and in the weaving this reinforced section of the band member is also provided with spaced lines of threads representing 55 stitches indicated at 14. This reinforced section of the band member strengthens the same at the points of greatest tension and wear. In a similar manner the edge of the flap member 11 is preferably reinforced as 60 indicated at 15 and provided with rows of threads representing stitches 16. This reinforced section of the flap member assists the parts of the collar in retaining their shape when in use. The line of division between 70 the band member and the flap member is indicated at 17 and the neck band of the collar is preferably reinforced as indicated at 18 to strengthen the same adjacent the fold line. In the weaving the band member 10 may also 75 be provided with a longitudinal reinforced section indicated at 19 to add additional strength to the band member and also to contact with the reinforced edge 13 of the band member to form a channel for a scarf which 80 may be worn with a collar.

The collars as cut from the strips of material made as hereinbefore described may have their end sections turned over and stitched along the lines indicated at 20 and 85 21, or if desirable these end edges of each collar may be provided with a suitable binder which is secured thereto by these lines of stitches. The collar is furthermore provided with suitable button holes indicated at 22 90 and 23.

Referring to the form of the invention illustrated in Figs. 4 and 5, it will be seen that the end sections 24 of the band and flap members may be woven tubular, and after 95 the strip of material has been cut along the transverse lines to form the collars therefrom the extremities of these tubular end members as indicated at 26 and 27 may be turned in and connected by suitable stitches. 100 As indicated in Fig. 5 there may be a line of stitches 28 passing through these inturned ends and also through the outer portions of the fabric, and a second line of stitches 29

passing only through the outer members of the fabric adjacent to the extremities of the inturned members so as to form a base for these inturned members to prevent the same 5 from fraying or unraveling. By reference to Fig. 6 it will be seen that the collar made in accordance with my present invention may be so woven as to provide one or more loops indicated at 30 and woven so as to 10 integrally connect the band or inner member and the flap or outer member. As indicated in Fig. 1 of the drawing two such loops may be woven in the collar, and while this number is preferable, one being placed 15 on either side of the button hole at the back of the collar, the number of loops thus woven may be varied. The object of this construction is to prevent the scarf from creeping up between the folds of the collar. 20 It will now be understood that the collar made in accordance with this invention is woven to shape while in a folded and set position and the parts thereof are provided with reinforcements in the weaving so as to 25 strengthen the collar at the points of greatest tension and wear and also to cause the

collar to retain its shape and position on the neck of the wearer.

I claim as my invention:

1. A collar comprising a band member and 30 a flap member woven in one piece and having a loop of predetermined extent woven integrally between and connecting the band and flap member.

2. A collar comprising a band member and 35 a flap member woven folded in one piece in a set position and having a loop of predetermined extent woven integrally between and connecting the band member with the flap member.

3. A collar comprising a band member and 40 a flap member woven in one piece and in a set position, the flap member being provided with a reinforced section along the edge thereof, the band member being provided 45 with a reinforced section along the edge thereof, and a loop being woven integrally with and between the said band member and flap member.

Signed by me this 7th day of April, 1922. 50

MORTON M. WEIL.
